Patented Feb. 15, 1966

203,790

COMBINATION CABANA AND SOLARIUM THEREFOR

Mike Tecton, 5101 45th St. NW., Washington, D.C.

Filed Mar. 10, 1965, Ser. No. 84,205

Term of patent 14 years

(Cl. D83—1)

FIG. 1

FIG. 2

FIG. 3

FIG. 4

FIG. 1 is a side perspective view for a combination cabana and solarium therefor embodying my new design; FIG. 2 is a side elevational view thereof; FIG. 3 is a rear elevational view thereof; FIG. 4 is a top plan view thereof;

The characteristic feature of my new design resides in the combination of the circular like inclined roof and it's truncated oblique circular and parabolic like conical solarium side walls.

I claim:

The ornamental design for a combination cabana and solarium therefor, substantially as shown and described.
